(57) **CLAIM**

The ornamental design for a handheld device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of a handheld device showing our new design.

FIG. 2 is back perspective view thereof.

FIG. 3 is another back perspective view thereof.

FIG. 4 is a front view thereof.

FIG. 5 is a back view thereof.

FIG. 6 is a right side view thereof.

FIG. 7 is a left side view thereof.

FIG. 8 is a top view thereof.

FIG. 9 is a bottom view thereof.

FIG. 10 is a front perspective view of a second embodiment of a handheld device showing our new design.

FIG. 11 is a back perspective view thereof.

FIG. 12 is another back perspective view thereof.

FIG. 13 is a front view thereof.

FIG. 14 is a back view thereof.

FIG. 15 is a right side view thereof.

FIG. 16 is a left side view thereof.

FIG. 17 is a top view thereof.

FIG. 18 is a bottom view thereof.

(Continued)

FIG. 19 is a front perspective view of a third embodiment of a handheld device showing our new design.

FIG. 20 is a back perspective thereof.

FIG. 21 is another back perspective view thereof.

FIG. 22 is a front view thereof.

FIG. 23 is a back view thereof.

FIG. 24 is a right side view thereof.

FIG. 25 is a left side view thereof.

FIG. 26 is a top view thereof; and,

FIG. 27 is a bottom view thereof.

The broken lines shown in FIGS. 1-9 illustrate portions of the handheld device that form no part of the claimed design.

The broken ones shown in FIGS. 10-27 are included for the purposes of illustrating environment and form no part of the claimed design.

The white portions in FIGS. 10-18 indicate a contrast in the appearance of the handheld device.
